UNITED STATES PATENT OFFICE

GUY A. DUNN, OF SAN FRANCISCO, CALIFORNIA, ASSIGNOR TO EBY MACHINERY COMPANY, OF SAN FRANCISCO, CALIFORNIA, A CORPORATION OF CALIFORNIA

JOGGING MECHANISM FOR TYING MACHINES

Application filed July 30, 1928. Serial No. 296,335.

This invention relates to a jogging mechanism for use in a tying machine, and its object is to provide a tying machine with an automatic jogger which will bring a series of 5 bundles, or a series of box shooks into alignment without unduly compressing them, or injury thereto, and as soon as the jogger has struck the bundle it will stop at that point and not compress it more than is incidentally done due to the smart blow which it 10 strikes the bundle with.

It will be understood by those familiar 15 with the bundling machine art, that in bundling shooks, shingles and other thin objects of that character, that great care must be taken to align all of the units of the package, or else the package will be very loosely tied, or the several units will be injured by having the wire cut into them and 20 spoil them along the edges.

With the present invention the jogger strikes the packages, aligns all of the several units as they may be loosely piled up in the 25 tying machine, and as soon as the jogger has thereby aligned the units it stops and is held in that position throughout the time of the operation of the tie, thereby preventing the bundle from becoming disarranged during the tying operation, and as soon as the 30 tying is completed the jogger is then restored to its outermost position by the operation of the parts automatically.

Another object of the jogger is to provide 35 means for straightening up and aligning the several units of a package even though they are not very carefully aligned as the package is put into the machine, the jogger moving from eight to ten inches or a foot during each stroke, and then being automatically restored to its initial position at the end of the tying operation.

Other objects of the invention will be apparent as the description proceeds.

An embodiment of the invention is shown 45 in the accompanying drawings in which the same reference numeral is applied to the same portion throughout the several figures of the drawings and of which there may be modifications.

50 Figure 1 is a back elevation of a complete

tying machine having this jogging apparatus applied thereto, that is looking at the discharge side of the tying machine.

Figure 2 is a side elevation of the tying machine showing the relation of the jogger 55 to the fence against which the bundles of units are placed to be tied.

Figure 3 is a vertical sectional view through the jogging mechanism in a plane 60 parallel to the main frame of the tying machine.

Figure 4 is a vertical sectional view through the gears which drive the jogger.

Only so much of the tying machine as 65 is necessary to illustrate the action of the jogger is shown, most of the operating parts of the tying machine being left off for purposes of clearness of illustration.

The numeral 1 represents the base of the tying machine; 2 a large fixed ring which 70 extends in a vertical plane from the base and which has supporting wheels 3, 4, 5 and 6 to carry the shuttle ring 7. The base 1 is provided with a table 8, on one side of 75 which there is a fixed fence or abutment 9 against which the bundles are pushed when they are to be tied.

The machine is driven by an electric motor 10 which is mounted upon a bracket or table 11 at the top of the ring 2, and has the belt 80 12 extending to a pulley 13 on the shaft 14 which carries a worm gear 15 in mesh with a worm wheel 16 on a shaft 17. The shaft 17 carries a cam 18 and a wheel 19 which 85 is provided with a crank pin 20. The crank pin 20 is connected to a pitman 21 which pitman has a series of rack teeth 22 thereon at its upper end in mesh with a pinion gear 23. The pitman 21 slides through a box 24 which is pivotally mounted on the shaft 25. The shaft 25 is mounted in two journal boxes 26, 27 and it has a bevel gear 28 thereon in mesh with a bevel gear 29 on the shaft 30. The shaft 30 has a gear 31 thereon in 90 mesh with a smaller gear 32 on a shaft 33 which shaft also has a larger gear 34 thereon which gear drives the ring gear 7, and also drives the gears operating the jogging mechanism.

The gear 34 is in mesh with the gear 35 100

on a shaft 36, which shaft is mounted in a suitable bearing 37. The shaft 36 has a collar 38, and since it is used in longitudinal thrust as well, it is held in a given position by having the hub of the gear 35 bear upon one end of the bearing 37, and a tubular member 39 and bolt 40 is used to bring the gear 35 snug up against the end of the journal bearing, while at the same time the collar 38 is brought snug against the other end of the same bearing.

At the opposite end from the gear 35 the shaft 36 is provided with a long spline 41, and holds a threaded sleeve 42 on which a collar 43 is threaded, a nut 44 being used to prevent the collar 43 from coming off the end of the thread. The threaded sleeve 42 is provided with two keys 45, 46, which engage key-ways in a bell shaped casting 47, said casting having a friction wearing disk secured thereto at 48. A heavy spiral spring 49 surrounds the bell shaped casting and bears upon the disk 43. In the space between the bell shaped casting and contacting with the end of the sleeve 42 and the flange 38 is a larger threaded sleeve 49', said sleeve being slidable on the key 41.

Suitably mounted on the threaded sleeve 49' is a collar 50, which collar carries a spur gear 51 rigidly connected thereto by means of a threaded collar 52. In the bracket 53 which supports the bearing 37 there is slideable a rod 54 which has gear teeth on its underside and which carries the jogger arm 55. The rack bar 54 which carries the jogger arm 55 is in engagement with a pinion 56 on a shaft 57 journalled in two bearings 58, 59 just below the bearing 37, and the shaft 57 also carries a gear 60 with a very wide series of teeth.

A supporting rod 61 extends into a bracket 62 carried by the journal bearing 37 and supports a shell 63 which forms a guard for the gear 51, gear 60 and driving member 47. The cam 18 operates on a small roller 63' on a bell crank 64 which is pivoted at 65 to the lower portion of the fixed ring 2, and it has a rod 165 pivotally connected to its other end and to a short arm 66 which is secured on the shaft 67 in a fixed position by means of a bolt 68.

In order to provide the proper cushioning effect the rack bar 54 has a heavy washer or collar 80 thereon, which collar forms the backing for a leather pump washer 81 and thin metal washer 82 held in place on the end of the bar 54.

This pump washer is held in place by a nut 83 on the end of the rack bar, and this washer slides in a cylinder 84 which is threaded on the end of the bearing 85 in which the rack bar slides.

A plug 86 closes the end of the tube 84, and a small valve 87 enables the air passing into said tube and out of it to be so con-

trolled as to dampen the rapid movement of the rack bar 54.

The shaft 67 carries an eccentric 69 which bears upon a key 70 which key in turn bears upon the rack bar 54, the object being to prevent the rebound of said shaft when it is pushed forwardly and the arm 55 jogs the pile of units into place.

The operation is as follows: Assuming a loose pile of shooks to be placed upon the table 8 adjacent the fence 9 the machine will be started into operation to effect the tying. The first movement that takes place will cause the rotation of the shaft 36, and as the gear 51 is then in contact with the friction surface 48 with the spring 49 compressed the result will be to rotate the gear 56 and throw the jogger bar forward; about the same time the eccentric will be turned so that it engages the key 70 and presses upon the shaft 54, a spring 65' within the tube 265 permitting enough slack movement to prevent the eccentric from locking on the key 70. As soon as the jogger 6 strikes the bundle, the friction 48 will slip and the gear 51 will become disengaged from the friction with the jogger bar held firmly in engagement with the bundle, but without any tendency to move in either direction.

As the tying ring returns to its initial position the gear 51 will reverse its direction of travel longitudinally of the shaft 36 and will come into engagement with the friction 48 so that at the end of the movement of the machine the jogger bar will be restored to the position shown in Figure 1 ready for a subsequent operation.

Having thus described my invention, what I desire to secure by Letters Patent of the United States is as follows, but modifications may be made in carrying out the invention as shown in the drawings and in the above particularly described form thereof, within the purview of the annexed claims:

1. A jogger mechanism for bundling machines comprising the combination with a bundling machine of a table to support the bundle, an abutment against which the bundle is to be placed, a slideable jogger arm, a rack bar for the support of the arm, means to advance the rack bar to cause the jogger bar to strike the bundle a sharp blow, means to thereupon disengage the jogger arm advancing mechanism therefrom, and means to engage the jogger bar mechanism to retract said bar upon the completion of a tie.

2. A jogger mechanism for tying machines comprising the combination with a tying machine of a table for the support of a bundle to be tied, a fixed abutment against which the bundle is also placed, a slideable jogger arm, a rack bar supporting the jogger arm, means to advance and retract said jogger arm, means to hold the jogger arm

advanced for a part of the time during the operation of the tying machine, and means to damp the action of said jogging mechanism.

3. A jogging mechanism for bundling machines comprising the combination with a bundling machine of a table for the support of the bundle, an abutment on the table against which the bundles are placed, a jogger arm, means to cause the jogger arm to advance to strike the bundle a sharp blow, means bearing on the one side of the jogger arm support to prevent the retraction of the jogger bar, and means to damp the action of the jogger arm.

4. A jogger bar for bundling machines comprising the combination with a bundling machine of a support for the bundle, an abutment against which the bundle is also placed, a jogger bar adapted to strike the bundle a sharp blow, means to advance and retract the jogger mechanism, and a friction drive arranged to alternately advance and retract the jogger mechanism.

25 In testimony whereof I have hereunto set my hand this 20th day of July, A. D. 1928.

GUY A. DUNN.
